THERAPEUTIC BATH FLUID CIRCULATING APPARATUS

George A. Schroeter, Briarcliff Manor, N. Y.

Application December 28, 1946, Serial No. 718,979

10 Claims. (Cl. 259—95)

1 The present invention relates to a fluid circulating apparatus or device for producing relatively gentle massaging effects in therapeutic baths.

During relatively recent years there has been increased recognition given to the healing properties of therapeutic baths. Such baths have proven to be particularly efficacious where liquid is maintained in circulation and caused to flow over the body of a patient submerged in the bath; this flow provides a most desirable comparatively gentle massaging effect.

While the desirability of providing the above noted massaging circulation has been generally appreciated the actual production of circulation in a bath has offered difficulties. With the large fixedly installed baths of hospitals and other institutions the circulating mechanism has frequently been installed for use only with a particular bath. Such apparatus or installations are erected in fixed position or are so unwieldy as to require specially constructed mounting means, brackets, tracks, or the like. They are not generally satisfactory for use in homes or small institutions. Other forms of apparatus have been so heavy or unwieldy that persons who would normally desire them have been deterred from their use. Still other forms of apparatus have extremely limited fields of use or have not resulted in producing an efficient massaging current or stream.

The present invention aims to overcome the above and other difficulties or disadvantages by providing a new and improved apparatus for creating a circulating stream or flow of fluids in a therapeutic or hydrotherapy bath. The invention further contemplates the provision of a relatively compact fluid circulating apparatus which may be offered to home owners for use in an ordinary home bath tub.

An object of the present invention is to provide a new and improved fluid circulating apparatus or device.

Another object of the invention is to provide a new and improved fluid circulating device which may be readily used with an ordinary home type of bath tub.

Another object of the invention is to provide a new and improved fluid circulating device which may be readily moved to different positions for use.

Still another object of the invention is to provide a fluid circulating device adapted to create an improved flow of liquid and air or gas.

Other and further objects of the invention will

2 be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a perspective view showing a preferred embodiment of the invention;

Fig. 2 is a perspective view showing the device or apparatus of Fig. 1 in use with a bath tub;

Fig. 3 is a vertical sectional view through the device or apparatus illustrated in Fig. 1;

Fig. 4 is a horizontal view taken along the line 4—4 of Fig. 3;

Fig. 5 is a perspective view of the preferred embodiment with certain parts removed;

Fig. 6 is an enlarged sectional view, partly broken away, showing a preferred form of a fluid circulating means;

Fig. 7 is an exploded perspective view showing certain parts illustrated in Fig. 6;

Fig. 8 is a bottom view of the device illustrated in Fig. 6; and

Fig. 9 is a view showing the interior of the part illustrated in Fig. 8.

Described generally the present device or apparatus comprises (Figs. 1, 2, and 3) a wheeled base 1 upon which is mounted a drive motor 11 for actuating a fluid circulating head 3 carried adjacent one end of a movably mounted arm 6. The arm 6 may be positioned along the top of a housing 120 when the device is not being used and for use may be lifted, swung laterally, and lowered so that the fluid circulating part of the head 3 projects into a body of liquid in a tub 7.

In Fig. 1 a preferred embodiment of the invention is shown with the water circulating head and other operating parts in storage or non-use position.

In Fig. 2 the apparatus or device is shown with a water circulating head 3 extending into the interior of a bath tub and beneath a surface of a volume of water for creating a circulating stream of fluid. It will be noted that the apparatus is positioned closely adjacent a side wall of the bath tub 7 with the laterally extending arm 6 projecting over the rim of the tub. As will be brought out hereinafter, it is not necessary to provide securing clamps or rails, or to lift any heavy weights in connection with shifting the

device from a position of non-use illustrated in Fig. 1 to a position of use shown in Fig. 2.

The vertical cross section through the present apparatus or device shown in Fig. 3 brings out the relationship of the various parts with respect to each other as they exist in the position shown in Fig. 1. The perspective view of Fig. 5 shows certain of the parts in different relationship, certain of the members or parts being removed for purposes of clarity in connection with the description. As shown in these two figures the parts are mounted upon a base or platform 1 carried by rollers or casters 2 which are secured to the lower part of the base and normally hidden from view by a downwardly extending flange 4 of the platform. By mounting the parts upon this wheeled base the machine or apparatus which is constructed upon the base may be easily moved about.

Secured to the upper surface of the base 1 adjacent one end thereof by bolts 12 is an upwardly extending mounting bracket 5 adapted to support, by means of bolts 8 and 9 and rubber or other silencing pads 10, an electric motor 11. The motor 11 itself may be carried by a substantially U-shaped mounting member 13, with the motor shaft 14 in vertically disposed position. The shaft 14 is preferably connected with a clutch element 16 through an aligning connection or coupling 17 and shaft 19, the shaft 19 being rotatably maintained in position by a bushing 20 carried adjacent one end of a bracket 21 secured by bolts 22 to the upper end of the vertically disposed mounting bracket 5. A complementary clutch element 23 which co-operates with the clutch element 16 will be later described in connection with the fluid circulating head 3.

The laterally extending arm 6 which supports the circulating head 3 adjacent its outer end is preferably adjustably or movably supported on horizontal bracket or plate member 24 having spaced securing lugs 25 at one end thereof to which are attached upright, movable standard members 27. The standard members 27 extend through bushings or guides 28 bolted to the upper end of the vertically disposed mounting bracket 5. The lower ends of the spaced vertical standards 27 are secured to a cross bar 29 and each of the lugs 28 adjacent the upper part of the mounting bracket 5 is shown connected by a cross portion 31. The cross bars or portions 29 and 31 are preferably pivotally connected to hinged link members 34 and 35, which are normally urged toward a collapsed or folded position (Fig. 5) by a tension spring 37. The normal tendency of this spring 37 is to urge or pull the movable lower end of member 34 toward the upper end of spaced members 35, the members pivoting around the pin 32, and to thus elevate the lower ends of the spaced standards 27. The force or tension of the spring 37 is preferably such, however, that its effect is normally insufficient to elevate the standards and parts supported on the horizontal bracket 24, without the application of some relatively small additional lifting force being applied to the laterally extending arm 6.

The lateral arm 6 may be retained in assembled relationship with the bracket 24 by a shaft 38 which extends through apertures and a lining bushing 40 of the arm 6 and bracket 24, and has an enlarged shoulder 41 on the upper clutch element 23. The upper end of the shaft 38 is shown provided with a bearing or washer member 42, keyed spur gear 45, keyed pulley or wheel 43, all retained in operative position on the shaft 38 by a

nut 44. The securing nut 44 is preferably so positioned as to allow horizontal movement of the laterally extending arm 6 with respect to the bracket 24 over which it is assembled. This construction facilitates movement of the arm 6 and circulating head 3 toward the right or the left upon elevation of the arm 6 and circulating head 3 from the inoperative position and movement to a position for use.

A latch member or pin 46 may be utilized to locate the laterally extending arm 6 in correct right, left or secured positions. A spring 47 normally urges the pin 46 downwardly into any one of a plurality of recesses 49 and the pin may be pulled upwardly in opposition to the spring 47 by a ring or extension 50.

The fluid circulating head or means 3 is shown generally at the right side of Fig. 3 and in greater detail in Figs. 6 through 9. Preferably it comprises a rotatable, vertically positioned shaft 52 having a pulley or belt wheel 53 secured adjacent the upper part thereof adapted to receive the drive belt 55, the latter being driven by the pulley or wheel 43 secured to the upper end of the motor shaft 38. When the motor 11 is in operation the shaft 38 is effective to rotate the vertical shaft 52 through the belt wheels 43 and 53 and the connecting belt 55.

The upright shaft 52 is preferably hollow, for a purpose which will be hereinafter brought out, and has an impeller 56 secured to the lower part thereof. The impeller 56 is shown provided with substantially radially extending slots or openings 57 spaced circumferentially along an upwardly extending flange 58 of its cover. A flanged member 59 having radially extending slots 61 is adapted to extend into a recessed portion 60 with the apertured central hub 62 thereof extending upwardly through an aperture 64 in a plate member 65, the hub 62 being force-fitted or otherwise suitably retained by a set screw or the like in the lower open end of the upright shaft 52. The plate member 65 is preferably secured to the cover of the impeller 56 by screws or bolts (not shown) which extend through apertures 67 of the plate 65 and apertures 68 of the impeller 56. With this construction the hollow interior passageway or conduit 63 of the vertical shaft 52 connects with the volume surrounding the impeller through the opening 66 and slots 61 of the flanged member 59 and radially extending slots 57 of the impeller ridge 58. This construction facilitates passage of air from the atmosphere to a position adjacent the impeller, as will be more clearly brought out hereinafter.

A housing 70 having inlet openings 71 adjacent the lower part thereof and a discharge opening 72 in its wall extends around the impeller and forms means for conveying fluids to the impeller and for directing the flow thereof during impeller rotation. The housing 70 is preferably connected with the lower end of a sleeve member 73 which extends upwardly about the vertical shaft 52 and the sleeve 73 has a lug 75 extending laterally from its upper end operatively connected with means for selectively determining the position of the discharge opening 72 of the housing 70.

Control of the quantity of liquid entering the housing 70 may be obtained by an apertured plate member 76 rotatably connected by a bushing 77 with an apertured plate 74 at the lower part of the housing 70 and having a lug 78 at one side thereof connecting with a controlling arm 80 of a tubular sleeve member 81 having a knurled 75 adjusting ridge 82 at the upper part thereof.

When the adjusting ridge 82 is rotated with respect to the vertical shaft 52 the control arm 80 is effective to rotate the apertured lower plate member 76 with respect to the opening 71 in the apertured plate member 74 held by screws at the lower part of the housing 70, to thus vary the effective sizes of the openings 71 through which liquid passes into the housing 70 and to the impeller 56. In this manner the quantity of liquid admitted to and discharged by the impeller 56, through the discharge opening 72, may be selectively controlled.

When the upright or vertical shaft 52 is rotated by the motor 11, liquid will be drawn or sucked into the housing 70 through the openings 71 and discharged through the opening 72; simultaneously air will be drawn through the opening 83 in the plate member 84 shown extending over the upper end of the bushing 86 that rotatably holds the upper end of the vertical shaft 52. Air drawn in through this opening 83 passes downwardly through the conduit or passageway 63 of the vertical shaft 52, through the opening 66 of the flanged member 59, outwardly through the radial slots 61 of this latter flanged member, through the radially extending slots 57 of the ridge 58 on the impeller 56, and into the interior of the housing 70. The stream of air entering the housing from a downward direction and the stream of liquid which enters the housing upwardly through the inlet apertures 71 of the housing intermix thoroughly due to the turbulence created by the rapid rotation of the impeller 56. The intimately or thoroughly intermixed and agitated stream of liquid and air is ejected through the discharge opening 72. Thus the fluid circulating means 3 is effective to create a thoroughly intermixed or agitated stream of air and water and to guide it in the direction indicated by the particular position of the discharge opening 72.

While the direction of the stream discharged through opening 72 may be selected manually, it is preferable to automatically vary the direction of a massaging stream at periodic intervals. This feature is most desirable for it insures against accidents by a person slipping in the bath tub while attempting to adjust the device and also effects creation of an optimum type of massaging stream in that the circulating stream is caused to reach practically every part of the body of an individual using the device in a hydrotherapy bath.

One form of mechanism for automatically achieving periodic variation in the direction of the massaging stream is shown more particularly in Figs. 3 and 4. As shown, an extension lug 75 at the upper end of the housing sleeve 73 is connected with the gear 45 on the motor driven shaft 38 through the intermediation of meshing gears 88, 89, 90, and 91, and by spring 92 connected at one end thereof with the gear 91 and at the other end thereof with a pivoted lever 94. One end of the lever 94 is pivotally secured to the lower base of the laterally extending arm 6 by a pin 95 and the other end has a pin 97 with a roller 96 extending into a slot or aperture 98 of the extension lug 75 on the housing sleeve 73.

As the motor driven shaft 38 rotates and turns the intermeshing gears, the gear 91 and spring 92, pivotally secured thereto tend to pull the pivoted lever 94 first toward one side of the gear 91 and then to the other side thereof, depending upon the particular momentary position of the pin 93 which secures the spring to the gear 70

91. When the bar 94 is against the stop 99 in the position shown in Fig. 4, the lever 94 and pin 97 at the end thereof are effective to hold the extension lug 75 in the position shown in this figure. 5 When the gear 91 has rotated to a position where-in the pin 93 is at approximately a diametrically opposite part of the gear 91, the spring 92 tends to pull or snap the lever 94 around its pin 95 to the other side of the arm 6 and against the stop member 100. This also moves the extension lug 75 to the same side of the arm 6 and turns the sleeve 73 and housing 70 which is connected with it; turning the housing to a new position means that the discharge opening 72 thereof will be located in a different position and that the stream ejected through the discharge opening will be guided in a different direction. The outer tubular sleeve 81 which moves the aperture controlling disk rotates with the housing sleeve 73 15 and thus the selected size of inlet opening 71 is maintained until such time as the flange 82 is gripped and turned with sufficient force to select a different size of inlet opening 71.

20 The automatic oscillating mechanism described 25 above is shown for illustrative purposes and other suitable types may be utilized.

25 Preferably an outer sheet metal casing 120 extends around the working parts of the present apparatus or device and prevents dust, dirt and 30 the like from accumulating on operating parts and interfering with their operation. In addition, the casing minimizes the possibility of a person being injured by moving parts and contributes toward presenting a neat and pleasing 35 appearance.

30 The motor 11 may be connected by a cable 103 and plug 111 to some suitable source of power. Preferably the cable is operatively connected in any known and suitable manner through an 35 "off-on" switch 104, speed control box or mechanism 106, and selectively adjustable timing device 108.

35 A plurality of vacuum or suction cups 110 may be provided at the sides of the sheet metal casing 120 to facilitate retaining the apparatus in desired position against the side of a bath tub. Any number of suction cups may be utilized and they are preferably located at each side of the casing 120 so that either side may be pressed 50 against the wall of a tub and the cups will tend to maintain it in position.

40 In order to put the present device or apparatus into operation it is merely necessary to press the plug 111 into a power socket, set the pointer 45 of the timing device 108, adjust the speed control box 106, lift upwardly on the handle 112 of the laterally extending arm 6 to elevate the circulating head 3 out of the casing 120, and turn the arm to a position extending over the side of a 55 bath tub (Fig. 2). The laterally extending arm may then be lowered so that the fluid circulating means 3 extends downwardly into and beneath the surface of water in the tub. When the laterally extending arm 6 is lifted upwardly the 60 complementary clutch elements 16 and 23 readily separate from each other and as the arm is lowered into operating position the clutch elements approach each other and their teeth readily move into engagement; the substantially 65 saw-tooth edges on the clutch faces facilitate engagement of the teeth at any position.

70 Lifting the laterally extending arm 6, fluid circulating means 3, and oscillating mechanism carried within the arm, is facilitated by the 75 counterbalancing mechanism comprised of the

pivoted link members 34 and 35 and the lifting spring 31. Bath temperature may be indicated by a thermometer 79.

The taper pin or latching means comprised of the pin 46, spring 47, ring member 50 and recesses 49 are effective to retain the laterally extending arm in desired position.

The position of the motor 11 adjacent the lower part of the mechanism and substantially on the base 1 produces an apparatus having a low center of gravity and militates against accidental upsetting thereof.

When the control switch 104 is turned to the "on" position the motor 11 is effective to drive the impeller 56 of the fluid circulating means 3 through the intermediation of coupling member 17, shaft 19, meshing clutch elements 16 and 23, shaft 38, pulley wheel 43, belt 55, pulley wheel 53, vertical shaft 52, flanged member 59 and plate member 65. Liquid is drawn inwardly through the inlet openings 71 at the lower part of the impeller housing 70. The sizes of the inlet openings 71 may be adjustably controlled by the movable plate member 76, and this adjustment may be made through the knurled boss 82 positioned above the surface of the water in the tub. Air drawn inwardly through the aperture 83, shaft conduit 63, conduit 66 and radial openings 61 and 57 is thoroughly intermixed with liquid drawn into the housing 70 through the inlet openings 71. The air and water approach each other from substantially opposing directions and tend to facilitate thorough intermixing or agitation of these two fluids while within the housing 70. The intermixed air and liquid are ejected through the discharge opening 72, the position of which may be automatically varied by the oscillating mechanism described more particularly in connection with Fig. 4 of the drawings.

It will be seen that the present invention provides a new and improved fluid circulating means which is compact, of relatively light construction, and which may be readily used in normal homes for the production of beneficial massaging currents in connection with therapeutic or hydrotherapy baths. The apparatus may be readily wheeled into and out of positions of use and the relatively low center of gravity minimizes the possibility of accidentally overturning the apparatus.

An improved massaging stream of liquid and air is provided by the thorough intermixture of the two fluids within the housing and subsequent discharge thereof. The particular direction given to the discharge stream may be automatically varied to create an optimum flow of the stream over all parts of the body of an individual using the present apparatus with a bath.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a therapeutic bath apparatus, the combination of a generally horizontal platform, roller members supporting said platform at locations spaced horizontally from each other for facilitating free movement of the platform over a floor, walls extending upwardly from peripheral portions of said platform, supporting means carried by and extending upwardly from said platform,

an arm adapted to overlie an opening provided by said upwardly extending walls and operatively connected with and supported by said supporting means, fluid circulating means depending from said arm, said arm being vertically and laterally movable for selective positioning of said fluid circulating means within said walls and laterally beyond them, and a drive motor carried by said apparatus below said arm and within said upwardly extending walls at a location spaced from said depending fluid circulating means and operatively connected therewith for actuation thereof.

2. In a therapeutic bath apparatus, the combination of a generally horizontal platform, rollers supporting said platform at locations spaced horizontally from each other for facilitating movement of the platform over a floor, supporting means carried by and extending upwardly from said platform, a laterally swingable arm operatively connected with and supported by said supporting means, fluid circulating means depending from said arm, a drive motor carried by said apparatus at a location spaced from said depending fluid circulating means and operatively connected therewith for actuation thereof, and means supported on said arm and operatively connected with said drive motor and with a portion of said fluid circulating means for periodically moving a portion of said fluid circulating means, while said arm remains stationary, and thereby changing the direction of a fluid stream caused by said fluid circulating means without swinging said arm.

3. A device of the class described comprising, a base, rollers supporting said base, a motor adjacent one end of said base, an arm extending generally horizontally from said motor, fluid circulating means including a housing rotatably carried by the arm at a location spaced horizontally from said motor, said circulating means being actuated by said motor, and means carried by said arm and connected with said housing and with said motor for periodically rotating said housing with respect to the arm and changing the direction of motion of a fluid stream set in motion by said fluid circulating means.

4. A device of the class described comprising, a base, rollers supporting said base for movement thereof freely over a floor, a motor, an outwardly extending arm, fluid circulating means including a portion oscillatable with respect to and carried by said arm at a position spaced laterally from said motor and connected with and driven by the motor, a bar-like member movably mounted on said arm and operatively connected with said oscillatable portion of the circulating means, and means connecting said movable bar-like member with said motor for periodically moving said bar-like member with respect to said arm and thereby moving said oscillatable portion of the circulating means to change the direction of motion of a fluid stream without moving said arm.

5. A device of the class described comprising a platform, rollers supporting said device at spaced locations for free movement of the device over a floor, a vertically movable and horizontally swingable arm carrying fluid circulating means and normally occupying a lowered position with respect to said platform, a drive motor for actuating said fluid circulating means, a plurality of upright members for guiding said arm during said vertical movement, and resilient means operatively connected with a lower por-

tion of at least one of said upright members for urging them and said arm upwardly during elevation thereof, said resilient means being of such capacity that said arm normally occupies said lowered position.

6. A device of the class described comprising a base, a drive motor, a generally horizontally extending vertically movable and laterally swingable arm carrying fluid circulating means adjacent one end thereof and carrying drive motor connecting means, means for normally supporting said arm at a lowered position with respect to said base, and means including a pair of vertically movable guide rods and a spring operatively connected with a portion of the supporting means and operatively connected with said arm and permitting said arm to normally remain at said lowered position but urging said arm upwardly away from said lowered position upon elevation thereof to minimize the effective weight of said arm and the means carried thereby.

7. A device of the class described comprising a base, a drive motor, a substantially horizontally extending vertically movable arm carrying fluid circulating means adjacent one end thereof and drive motor connecting means adjacent another end thereof, means including a plurality of horizontally spaced upright members adapted to guide said arm during vertical movement thereof, means interconnecting said upright members, and resilient counter-balancing means operatively connecting an extension of the base with said interconnecting means and urging said upright members and said arm upwardly during elevation thereof to minimize the effective weight of said arm and the fluid circulating means carried thereby.

8. A therapeutic bath device of the class described comprising a base, a vertically movable arm above said base horizontally swingable with respect to an arm supporting member, fluid circulating means carried by said arm, a drive motor carried by said device at a location spaced horizontally from said fluid circulating means, means for connecting the fluid circulating means with the drive motor, an arm supporting member, means operatively connecting said arm with said supporting member for vertical movement of the latter member with the arm, and means including a plurality of upright members operatively connected with said arm supporting member at spaced locations for guiding said supporting member during vertical movement and for retaining said arm supporting member against horizontal movement with said arm.

9. A device for use in providing a directed stream of liquid in bathtubs and the like, comprising a wheeled base structure adapted to be rolled along a floor and to be positioned alongside a bathtub, a drive motor carried by the device, an arm carried by the base structure and overlying said base structure and drive motor and movable vertically away from and toward the base structure, said arm being hori-

zontally swingable between a retracted position in which all of the arm directly overlies the base structure and an extended position in which the arm projects outwardly beyond the base structure and may overlie a portion of a bathtub, a member depending a fixed distance below said arm from a portion thereof which is extendible beyond the base structure, means carried by a lower part of said member for providing a directed stream in a liquid in a tub into which said member extends, a drive connection between said means and drive motor, and guide means cooperating with said arm and base structure for maintaining said arm horizontal during said movements thereof.

10. A device for use in providing a directed stream of liquid in bathtubs and the like, comprising a wheeled base structure having a length greater than the width thereof adapted to be rolled along a floor and to be positioned alongside a bathtub, a drive motor carried by the device adjacent one end of said base structure, an arm having a length about equal to that of the base structure carried by the base structure and overlying said base structure and drive motor and movable vertically away from and toward the base structure, said arm being horizontally swingable between a retracted position in which all of the arm directly overlies and covers the major area of the base structure and an extended position in which the arm projects outwardly beyond the base structure and may overlie a portion of a bathtub, a member depending a fixed distance below said arm from a portion thereof which is extendible beyond the base structure, means carried by a lower part of said member for providing a directed stream in a liquid in a tub into which said member extends, a drive connection between said means and drive motor, and guide means cooperating with said arm and base structure for maintaining said arm horizontal during said movements thereof.
